J. S. LINDHOLM,
SIDEWALK ELEVATOR,
APPLICATION FILED FEB. 15, 1916.

1,212,518.

Patented Jan. 16, 1917.

UNITED STATES PATENT OFFICE.

JENS S. LINDHOLM, OF BROOKLYN, NEW YORK.

SIDEWALK-ELEVATOR.

1,212,518.

Specification of Letters Patent. Patented Jan. 16, 1917.

Original application filed September 22, 1915, Serial No. 51,923. Divided and this application filed February 15, 1916. Serial No. 78,367.

To all whom it may concern:

Be it known that I, JENS S. LINDHOLM, a citizen of the Danish Monarchy, and a resident of Brooklyn, in the county of Kings 5 and State of New York, have invented certain new and useful Improvements in Sidewalk-Elevators, of which the following is a specification.

This invention relates to sidewalk elevators and has for its object the provision of certain constructions for safety in order to prevent accidents while operating the elevator.

Another object of the invention is the provision of an open-work elevator platform to admit light and air to the lower levels when the elevator is level with the sidewalk.

This application is a division of my allowed application Serial Number 51923, filed 20 September 22, 1915.

Accordingly my invention comprises such parts and elements in combination with a sidewalk elevator as hereinafter set forth, claimed and as illustrated in the accompanying drawing in which—

Figure 1 is a sectional view of a sidewalk elevator embodying my invention. Fig. 2 is a plan view, and Fig. 3 is a detail view of the platform.

Referring to the drawing the numeral 10 represents the elevator comprising the platform 17, a framework of bow irons 18 and 19, one in the rear near the building line 20 and one in front.

25 23 is a cross brace secured to the front bow iron 19.

21 represents the hoisting means.

14 and 15 are the sidewalk doors pivoted at 16.

40 In order to prevent accidents to persons and especially children caused by falling in over the elevator as it descends, I provide

a wire shield 35 between the bow irons and support the same further by cross bars 36 and a bow bar 37 which also serves to strike 45 the doors in the middle to open them in the usual manner when the elevator ascends. I further provide front protecting bars 70 to close the space at the top between the bow irons 19 to prevent people from falling in 50 over the elevator platform endwise. This is particularly useful when the elevator is raised slightly above the sidewalk for ventilating the space below.

A sidewalk elevator is sometimes left for 55 a considerable time at the sidewalk level and in order to provide light and air for the space below, I provide an open-work platform which may consist of flat irons 38 and lattice work 39.

60 It will be seen that the improvements provided by this invention are very simple, yet they are valuable and useful in providing protecting means against accidents without in any way interfering with the operation 65 of the elevator or materially changing the construction thereof.

It is not necessary that the improvements referred to be provided in the identical form or manner herein disclosed, and I claim all 70 such changes and modifications which properly come within the principle of the invention and the scope of the claim.

I claim:—

75 A sidewalk elevator comprising a platform and bow irons, a safety open-work top between said bow irons and protecting bars secured at the front of the said elevator to the one bow iron thereof.

Signed at New York in the county of New 80 York and State of New York this 14th day of February A. D. 1916.

JENS S. LINDHOLM.
